UNITED STATES PATENT OFFICE.

FREDERICK H. WEEKS, OF AKRON, OHIO.

DESIGN FOR A JUG.

SPECIFICATION forming part of Design No. 24,007, dated February 5, 1895.

Application filed January 3, 1895. Serial No. 533,773. Term of patent 7 years.

To all whom it may concern:

Be it known that I, FREDERICK H. WEEKS, a citizen of the United States, residing at Akron, in the county of Summit and State of Ohio, have invented and produced a new and original Design for a Jug, of which the following is a specification.

Reference is to be had to the accompanying drawing, in which the figure is a perspective 10 view of a jug embodying my new design.

The leading feature of my design is the jug having a gradually reduced and closed upper

end with a spout *a* at one side, at the top, the protuberance *b* diametrically opposite the spout and concaved at its top, and the ears *c* disposed at right angles to the spout *a* and protuberance *b*.

I claim—

The design for a jug herein shown and described.

FREDERICK H. WEEKS.
